UNITED STATES PATENT OFFICE.

ERNEST K. HOOD, OF INDIANAPOLIS, INDIANA, AND WALLACE B. WOLFF, OF CHICAGO, ILLINOIS, ASSIGNORS TO THE AMERICAN SLICING MACHINE CO., OF CHICAGO, ILLINOIS, A CORPORATION OF NEW YORK.

SHARPENER FOR SLICING-MACHINE KNIVES.

1,310,700.

Specification of Letters Patent. Patented July 22, 1919.

Application filed March 1, 1919. Serial No. 280,006.

To all whom it may concern:

Be it known that we, ERNEST K. HOOD, of Indianapolis, Indiana, and WALLACE B. WOLFF, of Chicago, Illinois, have invented 5 certain new and useful Improvements in Sharpeners for Slicing-Machine Knives, of which the following is a specification.

It is customary to provide slicing machines having rotary knives, with sharpening stones adapted to be rotated by coming 10 into contact with the bevel portion of the knife. In some machines a stone is used on the bevel side of the knife only and in other machines an additional stone is used to turn 15 the bur back from the concave side of the knife. Our invention applies to a sharpener of this latter type, and consists in the detailed construction hereinafter described and claimed.

20 The figure represents a cross section of the sharpener.

The numeral 1 represents a wheel made of emery or steel which is adapted to contact with the concave edge of a slicing machine 25 knife 2.

This wheel is carried by a shaft 3, rotatably mounted in a bearing 4, supported on a yoke 5 carried by a post 6, rigidly secured to the slicing machine.

30 It will be readily seen that this construction enables the placing of the wheel 1 in any desired position relative to the knife 2. In practice this wheel is inclined slightly to the perpendicular plane of the knife, and 35 also set at a slightly advanced angle with respect to the axis of the knife. This causes the edge of the knife to drive the wheel, but at a slight angle across the plane of rotation of the knife, thus grinding the edge 40 thereof.

The wheel 1 is held in contact with the edge of knife 2, by means of a spring 7 taking against a ball bearing 8, contacting with a collar 9 held on shaft 3 by means of a 45 pin 10.

To move wheel 1 away from the knife

edge we provide a barrel 11, provided with an internal thread 12, which co-operates with a thread 13, on bearing 3.

In the rear end of barrel 11, we mount an 50 adjusting screw 14, adapted to contact with the end of shaft 3. This adjusting screw is held in position by a lock nut 15.

The operation of the grinder is as follows:

It is adjusted to a knife by manipulating 55 the bearing 3 and yoke 5, until the proper angle is obtained.

The screw 14 is then set so that it just contacts with shaft 3 and is locked in position by means of nut 15. Then to grind 60 the knife barrel, 11 is backed off slightly by turning it thus releasing screw 14 from shaft 3, and allowing spring 7 to hold wheel 1 against the edge of the knife. When the knife is sharpened the barrel 11 is advanced 65 until screw 14 forces the shaft 3 forward, and wheel 1 away from the edge of the knife.

The adjustments thus provided, enable 70 the attaching of the grinder to machines in a commercial way. We are aware of the facts that there are several devices of this character and we do not claim it broadly.

We claim: 75
In a slicing machine sharpener the combination of a bearing; a shaft mounted therein; a wheel carried by said shaft adapted to contact with the edge of a knife; a spring mounted between the rear of the bearing and an anti-friction bearing carried by the 80 shaft; and a barrel, mounted on the bearing, adapted to advance and recede; an adjusting screw carried by said barrel, adapted to contact with the end of the shaft, and means for locking it into position, substantially as 85 and for the purpose set forth.

ERNEST K. HOOD.
WALLACE B. WOLFF.
